[57] **CLAIM**

The ornamental design for a gravitationally-fed cleaning mop for floors and walls, as shown and described.

DESCRIPTION

FIG. 1 is a perspective view of a gravitationally-fed cleaning mop for floors and walls showing a first preferred embodiment of my new design;

FIG. 2 is a right side elevational view of the embodiment of FIG. 1;

FIG. 3 is a left side elevational view of the embodiment of FIG. 1;

FIG. 4 is a front elevational view of the embodiment of FIG. 1;

FIG. 5 is a rear elevational view of the embodiment of FIG. 1;

FIG. 6 is a top plan view of the embodiment of FIG. 1;

FIG. 7 is a bottom plan view of the embodiment of FIG. 1;

FIG. 8 is a perspective view of a gravitationally-fed cleaning mop for floors, and walls showing a second preferred embodiment of my new design;

FIG. 9 is a rear elevational view of the embodiment of FIG. 8;

FIG. 10 is a bottom plan view of the embodiment of FIG. 8;

FIG. 11 is a top plan view of the embodiment of FIG. 8;

FIG. 12 is a side elevational view of the embodiment of FIG. 8; and,

FIG. 13 is a front elevational view of the embodiment of FIG. 8.

The broken line showing of a mop head in the FIG. is for illustrative purposes only and forms no part of the claimed design.
